UNITED STATES PATENT OFFICE

149,555

DESIGN FOR A CARGO COMPARTMENT FOR
AIRPLANES OR SIMILAR DEVICEHall L. Hibbard, Los Angeles, Calif., assignor to
Lockheed Aircraft Corporation, Burbank, Calif.

Application June 29, 1946, Serial No. 131,166

Term of patent 14 years

(Cl. D71—1)

To all whom it may concern:

Be it known that I, Hall L. Hibbard, a citizen of the United States, residing at Los Angeles, county of Los Angeles, State of California, have invented a new, original, and ornamental Design for a Cargo Compartment for Airplanes, of which the following is a specification, reference being had to the accompanying drawings, forming a part thereof.

Figure 1 is a perspective view of a cargo compartment embodying my new design, an airplane being shown in dotted lines for illustrative purposes only;

Figure 2 is a perspective view of the other side of the cargo compartment;

Figure 3 is a side view corresponding to Figure 2; and,

Figures 4, 5 and 6 are respectively top, front and rear views of the cargo compartment.

I claim:

The ornamental design for a cargo compartment for airplanes or similar device, substantially as shown and described.

HALL L. HIBBARD.
